WARP PRINTING APPARATUS

Otto F. Hilbert, Philadelphia, Pa., assignor to
Artloom Corporation, Philadelphia, Pa., a cor-
poration of Pennsylvania

Application November 25, 1936, Serial No. 112,645

9 Claims. (Cl. 101—172)

This invention relates to apparatus useful in spot printing warps with different colors for predetermined a definite design or pattern in carpets or other fabric subsequently woven from such warps. More especially, my invention relates to that type of printing apparatus wherein the warps are progressed in a sheet above a plurality of applicator rolls which rotate partly submerged in individual color troughs; wherein, under control of a suitable jacquard mechanism, type elements are selectively actuated to press the yarns into contact with the different color rolls according to the requirements of the design or pattern, for reception of spot imprints; wherein the warps, after the printing, are passed through a steam chamber to insure thorough penetration and setting of the colors; wherein, after the steaming, the warps are washed for removal of all unabsorbed or excess dye; and wherein after washing, the warps are finally dried by contact with a suitably heated element and collected on beams in readiness for transfer to the weaving looms.

In connection with warp printing apparatus of the character referred to, I aim to provide simple and reliable automatically operative means for supplying the different dyes to the color troughs in direct proportion to the varying rates at which said dyes are being used in the printing. Another object of my invention is to obviate the necessity for repeated actuations of the type elements for individual spot imprints as was heretofore necessary. This advantage I attain, as hereinafter more fully disclosed, by employing a brush-like covering for the applicator rolls capable of holding an adequate quantity of the dye so that ample color is applied to the warps by single actuations of said type elements.

Another object of my invention is to prolong the serviceability of the type elements, which, heretofore, were made wholly of metal, by providing them with tip portions of ceramic or other material capable of resisting the corroding action of the dyes.

Other objects and attendant advantages of my invention will appear from the following detailed description of the attached drawings, wherein

Fig. I shows, in side elevation, a warp printing apparatus conveniently embodying the present improvements.

Fig. II shows the front elevation of the printing mechanism of the apparatus on a larger scale.

Fig. III shows the rear elevation of the printing mechanism with a portion of the automatic color replenishing means removed.

Fig. IV is a fragmentary transverse sectional view taken as indicated by the arrows IV—IV in Fig. III.

Fig. V is a fragmentary sectional view taken as indicated by the arrows V—V in Fig. IV and drawn to a still larger scale.

Fig. VI is a detail section taken as indicated by the arrows VI—VI in Fig. V.

Fig. VII is a fragmentary sectional view taken as indicated by the arrows VII—VII in Fig. III and showing one of the color troughs and an associated pumping unit which forms a part of the automatic dye replenishing means.

Fig. VIII is a fragmentary detail sectional view taken as indicated by the arrows VIII—VIII in Fig. III and showing the means by which the actuation of the pumping unit of Fig. VII is controlled through a float in the corresponding color trough.

Fig. IX is a view corresponding to Fig. VIII with the parts differently positioned.

Fig. X is a fragmentary detail perspective view of guide means for the control floats.

Figs. XI and XII are fragmentary perspective views showing other details of the pump control means.

Fig. XIII is a fragmentary view showing a portion of the printing mechanism in longitudinal section.

Fig. XIV is a fragmentary detail view partly in elevation and partly in section, showing one of the color applicator rolls and a cooperating type element; and

Fig. XV is a detail sectional view of the printing end of the type element as indicated by the arrows XV—XV in Fig. XIV.

Referring first more particularly to Fig. I of these illustrations, the warps W are drawn from a creel (not shown) and passed in the form of a continuous sheet, about guide rolls 1 and 2 to 40 the printing mechanism which is comprehensively designated by the numeral 3. In this printing mechanism 3, the warps W pass horizontally above a series of troughs 4 (Fig. II) containing dyes of different colors, at a level slightly 45 above intermittently rotated applicator rolls 5 (see Fig. XIII) running partly submerged in the dyes, said warps being held to such level by sustaining bars 6 supported between the contiguous top edges of said troughs. Mounted on top of 50 the framework 7 of the printing mechanism 3 is a suitable jacquard mechanism 8, which, through cords 9, control type elements 10 (in the form of bars) whereby the warps W are depressed in accordance with the preconceived pattern or de- 55

sign requirements into contact with the color rolls 5 in the intervals between the sustaining bars 6. After being spot printed as just explained, the warps W pass horizontally through an elongate enclosure, through which steam is continuously circulated by way of flow and return pipes indicated at 12 and 13 to effect thorough penetration and setting of the colors in the warps. Incident to traversing the steam chamber 11, the warps W are supported by a progressing conveyor 14 trained about sprockets 15, 16 respectively on transverse shafts 17, 18. Upon leaving the steam chamber 11, the warps W pass to a washer comprehensively designated 19 for removal of any unabsorbed surplus dyes. As shown the washer 19 comprises a series of water pans 20, one set at a level slightly above another, into which the yarns are intermittently dipped by vibrating dippers 21 operated by an electric motor 22. Upon leaving the last of the water pans 20, the warps W are reversed in their travel by a guide roll 23 to pass over a drying element having the form of a horizontal steam pipe radiator 24 which is suitably supported above the steam chamber 11 as shown. After drying, the printed warps are cooled on beams 25 in a suitable beaming mechanism 26 whereof the framework 27 rests directly upon the top of the steam chamber 11. All the moving parts of the apparatus other than the dippers 21 of the washing mechanism 19 derive their motion from a transversely extending main shaft 28 (Figs. I, II and III) which is journaled in suitable fixed bearings on the framework 7 of the printing mechanism 3 and which is provided with a hand wheel 29 whereby it can be manually operated when required. As shown in Fig. II, the shaft 28 carries a spur gear wheel 30 which meshes with the pinion 31 on the shaft of an electric driving motor 32. The gear wheel 30 can be connected to or disconnected from the shaft 28 by means of a clutch whereof the manual shifting lever is indicated at 33 in Figs. I and II. The warps W are drawn into the printing mechanism by a pair of feed rollers 34, 35 associated with the guide roller 2, the latter of said feed rollers being mounted on a shaft 36 and rotated by an intermittent motion device 37 from a shaft 38 which is coordinated through a pair of intermeshing spur gears 39 and 40 with another shaft 41. Through a sprocket chain connection 42 the shaft 41 is continuously rotated from the main shaft 28. As shown in Fig. II, the color applicator rolls 5 are arranged to be actuated by a series of individually associated intermeshing spur gears 43 whereof one is driven by gearing shown at 44 from a shaft 45. A sprocket chain 46 connects the shaft 45 with the shaft 47 which is rotated through an intermittent motion device 48 from the shaft 41. The shaft 18 for the conveyor 14 by which the warps W are carried through the steam chamber 11, is connected, by a horizontal sprocket chain 49, with a sprocket shaft 50. From Fig. II, it will be noted that the shaft 50 is driven through a pair of intermeshing spur gears 51, 52 from the shaft 36, and thus partakes of the intermittent motion of the latter. The beaming mechanism 26 is operated through a sprocket chain connection 53 from a shaft 54 at the top of the framework 7 of the printing mechanism 3, the latter shaft being in turn connected, through a sprocket chain 55 with the main shaft 28. It will also be noted from Fig. II that the rock shaft 8a of the jacquard mechanism 8 is operated through a link

connection 8b with an arm 8c which is in turn operated by a crank 8d on the main shaft 28.

Having sufficiently described the apparatus as a whole to enable the proper understanding of its purpose and operation, I will now proceed to disclose those features with which my invention is more especially concerned.

For the maintenance of a constant level of the dye in the several color troughs 4, I have provided an automatic replenishing means which includes a series of pumps 56 (Figs. III, IV, V, and VII) individual to said troughs. As shown, these pumps 56 are bolted to a beam 57 which extends longitudinally of the back of the printing mechanism above the trough 4 and which is supported by the framework 7. The pistons 58 of these pumps 56 are operated through individual connecting rods 59 from a cross head 60 confined to vertical movement in fixed guides 61, also on the framework 7. By means of a pair of pitmen 62, the cross head 61 is coupled with cranks 63 on spaced parallel transverse shafts 65 which are journaled in bearings 66 on the framework 7, said shafts being connected for rotation in unison by a horizontal sprocket chain 67, and one of them being driven through a sprocket chain connection 68 from the main shaft 28. Connected to the inlet pipe 69 of each pump 56 is a hose 70 which leads from a barrel or vat 71, see Fig. IV, containing a supply of the dye; and interposed in said pipe is a check valve 72 which permits flow only in the direction indicated by the arrow in the illustration just referred to. To the outlet 73 of each pump 56 is connected a length of self-collapsing hose 75 (see Figs. IV—VI) of rubber or the like, which extends into the corresponding color trough 4. The delivery hose 75 thus operates as a check valve which responds to suction and thus remains closed during the draw of the pump 56 and which opens under pressure for flow of the dye from the pump 56 into the corresponding trough 4. For the purpose of controlling the pumping of the dye, a float 76 is associated with each color trough 4, each such float being appended to a rod 77. At its upper end, the rod 77 is connected to one end of a horizontal angle lever 78 which is medially fulcrumed at 79 to a bearing arm 80 extending rearwardly from a horizontal channel beam 81 supported by the framework 7 at the rear of the printing mechanism, see Figs. IV, VIII and IX. As shown in these figures, each of the connecting rods 59 comprises two components 82 and 83 of which the upper component 82 has a universal pivotal connection 84 with the cross head 60, and which is longitudinally slotted as at 85 to engage a pin 86 at the opposite end of the horizontal lever 78. At one of its side edges, the upper link component 82 has a lateral projection 87 which is adapted to engage with an undercut recess 88 in the contiguous edge of the lower rod component 83. Normally when the trough 4 is filled, the upper rod component 82 is held away from the lower rod component 83 as shown in Fig. VIII, with the lateral projection 87 of said upper component withdrawn from the recess 88 of said lower component so that the corresponding pump 56 remains inactive, the upper component moving idly up and down under the action of the cross head 60. When the level of the dye in the trough 4 recedes with attendant dropping of the float 76, the horizontal lever 78 will be moved from the normal position shown in Fig. VIII to the position shown in full lines in Figs. IV and IX, with the result that the upper

rod component 82 is permitted to fall back against the lower rod component 83, so that the lateral projection 87 of the one will engage the undercut notch 88 of the other. With the two 5 rod components 82, 83 thus coupled, reciprocatory motion will be imparted from the cross head 60 to the piston 58 of the corresponding pump which latter will thereupon draw dye from the barrel or vat 71 and discharge it into the trough 10. 4. Elevation of the float 76 to its normal level will obviously result in uncoupling of the two rod components 82 and 83, whereupon the pump 56 will remain inactive until again called upon to supply further dye. The operation just described is characteristic of all the pump units 56 so that the actuation of one of such units is entirely independent of the actuation of another. At the regions of overlap, the components 82 and 83 of the rods 59 are confined to laterally-spaced, 20 vertically-aligned slots 89, 90 respectively in the upper and lower flanges of the channel beam 81 (Figs. VIII, IX, and XI), the outer limits of said slots being defined by stop blocks 91 and 92 secured to the channel flanges. The float rods 77 25 are similarly confined in laterally recessed portions 93 of edge notches 94 (Figs. IV, VII, VIII, and X) in a guide bar 95, which, like the beams 57 and 81, is supported by the framework 7 longitudinally of the back of the printing mechanism. Hook-like keepers 96 projecting laterally from an axially-shiftable rod 97 engaging guides 98 on the bar 95 serve to prevent the float rods 77 from leaving the notches 94 of said bar under the turbulent action of the dye upon the floats 30 76 as the troughs 4 are being filled. As shown in Fig. X, the slide rod 97 has its end bent at right angles with resultant formation of an operating handle 99 for a purpose presently explained. At its top, each float rod 77 is formed with an eye 100 which is held in engagement with a pin 101 35 at the corresponding end of the associated horizontal lever 78 (Figs. VIII, IX, and XII), such engagement being maintained by a spring clip 102. Each float rod 77 is, moreover, provided with collars 103, 104 at short distances 40 respectively from the float 76 and lever 78. By virtue of the provisions just described, it is possible to render individual pump units inoperative for example, when any particular color or colors are not required by the pattern, the procedure being 45 as follows:

The slide rod 97 is shifted axially to the right in Fig. X so that the notches 94 of the guide bar 95 are cleared by the keepers 96. Thereupon, the float rod 77 of the particular pumping unit to be rendered inoperative, is withdrawn from its guide notch 94 in the bar 95. With this accomplished, the eye 100 at the top of the float rod 77 is detached from the pin 101 on the horizontal lever 78 by springing the clip 102, and said rod lifted and engaged in the loop portion of said clip as shown in dot and dash lines in Fig. IX. After the collar 103 is brought to the level of the bar 95, the float rod 77 is re-inserted into its notch 94, with attendant raising of the horizontal lever 78 by the collar 104 to hold the upper component 82 of the rod 59 away from the lower rod component 83 and thus prevent it from being coupled with said lower component—all as 50 shown in dot and dash lines in Fig. IX.

In order to increase the color carrying capacity of the applicator rolls 5 and thereby preclude the necessity for repeated actuations of the type members 10 for each spot imprint upon the warps 55 W as heretofore, I have provided said rolls with

a brush-like covering of fabric 105 (see Fig. XIV) having comparatively long closely spaced pile projections 106, as conventionally shown. Accordingly, upon downward displacement of the warps W by the type elements 10 into contact 5 with the applicator rolls 5, the pile fabric covering 105 will effectively yield, with resultant transfer of an ample charge of dye for penetration of said warps.

Furthermore, in accordance with my invention, 10 the type bars 10 are provided with replaceable tips 107 (Figs. XIII—XV) formed from glass, porcelain or the like, capable of resisting the corrosive action of the dyes, said tips being secured to the bars by rivets or screws 108. This 15 construction is economical in that it obviates replacements of the type elements as was frequently required heretofore when said elements were wholly of metal.

While the type elements 10 may be connected 20 directly to the actuating cords 9 of the jacquard mechanism 8, I prefer to employ the construction of Fig. XIII to relieve the cords of the weight of said bars. Accordingly there is associated with each type bar 10 a supplemental bar 109, which, 25 through a centrally pivoted lever 110 operates the type bar as shown, the type and actuating bar couples being confined in one direction between laterally-spaced eye beams 111 on the framework 7 of the printing mechanism, and in 30 the other direction by intervening spacing rods indicated at 112.

Having thus described my invention, I claim:

1. In warp printing apparatus, printing mechanism including a series of troughs for dyes of 35 different colors, applicator rolls running partly submerged in the troughs, type elements for depressing the warps in contact with the rolls, jacquard mechanism for controlling the type elements, and means for progressing the warps; 40 automatic pumping means for supplying the dyes as needed from separate sources of supply; a treating chamber through which the warps are passed after printing, said chamber enclosing a conveyor for the warps; means for washing the 45 excess dyes from the warps after treatment in the treating chamber; means for drying the warps after washing; means for beaming the dried warps; and a power shaft from which the printing mechanism, the automatic pumping 50 means, the conveyor, and the beaming mechanism are all directly actuated.

2. In warp printing apparatus, printing mechanism including a series of troughs for dyes of 55 different colors, applicator rolls running partly submerged in the trough, type elements for moving the warps into contact with the rolls, jacquard mechanism for controlling the type elements, and means for progressing the warps; automatic pumping means at the back of the printing mechanism for supplying the dyes as needed from separate sources of supply; a horizontal treating chamber in series with the printing mechanism, through which the warps are passed after printing, said chamber enclosing a conveyor for the 60 warps; means for washing the excess dye from the warps after treatment in the treating chamber, arranged in series with the latter and with the printing mechanism; means for drying the warps after washing and means for beaming the dried 65 warps to which the warps are passed by progression in a reverse direction, said drying and beaming means being serially arranged above the treating chamber; and a power shaft associated with the printing mechanism from which the auto- 70 75

matic pumping means, the conveyor, and the beaming mechanism are all directly actuated.

3. In warp printing apparatus of the character described, printing mechanism including a series of troughs containing dyes of different colors, means for progressing the warps, means for spot printing the warps with the dyes, and automatic means for supplying the dyes to the troughs as needed from separate sources of supply.

4. In warp printing apparatus of the character described, printing mechanism including a series of troughs containing dyes of different colors, means for progressing the warps, and means for printing the warps with the dyes; and means for supplying the dyes to the troughs comprising a series of pumps individual to the troughs and connected with separate sources of supply; means for actuating the pumps, and automatic means for connecting and disconnecting the individual pumps to and from the actuating means so as to maintain a constant level of the dyes in the corresponding troughs.

5. In warp printing apparatus of the character described, printing mechanism including a series of troughs containing dyes of different colors, means for progressing the warps, and means for printing the warps with the dyes; and means for supplying the dyes to the troughs comprising a series of pumps individual to the troughs and connected with separate sources of supply, means for actuating the pumps, and means operated by floats in the troughs for automatically connecting and disconnecting the individual pumps to and from the actuating means so as to maintain a constant level of the dyes in said troughs.

6. In warp printing apparatus of the character described, printing mechanism including a series of troughs containing dyes of different colors, means for progressing the warps, and means for printing the warps with the dyes; means for supplying the dyes to the troughs, comprising a series of pumps individual to the troughs and connected with separate sources of supply, a reciprocating cross head, individual rods by which the pumps are actuated from the cross head, each of said rods having two interengageable components, and automatic means for engaging and disengaging the rod components in order to control the pumps and thereby maintain a con-

stant level of the dyes in the corresponding troughs.

7. In warp printing apparatus of the character described, printing mechanism including a series of troughs containing dyes of different colors; means for progressing the warps, and means for printing the warps with the dyes; and means for supplying the dyes to the troughs comprising a series of pumps individual to the troughs and connected with separate sources of supply, 10 a reciprocating cross head, individual rods by which the pumps are actuated from the cross head, each of said rods having two interengageable components, and means operated by individual floats in the troughs for automatically engaging and disengaging said rod components to control the corresponding pumps and thereby maintain a constant level of the dyes in the troughs.

8. In warp printing apparatus of the character described, printing mechanism including a series of troughs containing dyes of different colors, means for progressing the warps, and means for printing the warps with the dyes; and means for supplying the dyes to the troughs, comprising a 25 series of pumps individual to the troughs and connected with individual sources of supply, a self-collapsible delivery hose constituting a check valve for each pump, means for actuating the pumps, and automatic means for connecting 30 and disconnecting the individual pumps to and from the actuating means so that a constant level of the dyes is maintained in the corresponding troughs.

9. In warp printing apparatus of the character described, printing mechanisms including a series of troughs containing dyes of different colors, means for progressing the warps, and means for printing the warps with the dyes; means for supplying the dyes to the troughs comprising a 40 series of pumps individual to the troughs and connected with separate sources of supply; means for actuating the pumps, automatic means for connecting and disconnecting individual pumps to and from the actuating means so that a constant level of the dyes is maintained in the corresponding troughs; and means whereby individual pumps may be rendered idle to the exclusion of others.

OTTO F. HILBERT. 50
